UNITED STATES PATENT OFFICE.

WILLIAM JAMES BRADLEY, OF JERSEY CITY, NEW JERSEY.

BRAKE-VALVE.

SPECIFICATION forming part of Letters Patent No. 586,158, dated July 13, 1897.

Application filed June 1, 1896. Serial No. 593,711. (No model.)

To all whom it may concern:

Be it known that I, WILLIAM JAMES BRADLEY, a citizen of the United States, and a resident of Jersey City, county of Hudson, 5 and State of New Jersey, have invented certain new and useful Improvements in Brake-Valves, of which the following is a specification, reference being had to the accompanying drawings, forming a part thereof, in which 10 similar letters and figures of reference indicate corresponding parts.

This invention relates to an improvement in brake-valves for controlling and operating air-brakes upon railway-trains, the object of 15 the invention being to provide an efficient and operative device of this character which is constructed in such a manner as to obviate the use of perishable rubber diaphragms and gaskets. Further, the device comprises 20 few and simple parts, it is easily and quickly operated, is positive in its action, and it is inexpensive and durable.

The invention will be hereinafter fully described, and specifically set forth in the an- 25 nexed claims.

In the accompanying drawings, forming part of this specification, Figure 1 is a plan view of my improved valve. Fig. 2 is a vertical sectional elevation on a line $x-x$ of Fig. 30 1. Fig. 3 is an inverted plan view of the valve in detail. Fig. 4 is a plan view of the body of the device. Fig. 5 is a sectional plan view thereof, taken on a line $y-y$ of Fig. 2. Fig. 6 is a plan view of the device, illustrating the 35 operation of the valve; and Fig. 7 is a vertical sectional elevation on a line $z-z$ of Fig. 4.

In the practice of my invention I provide primarily a cast-metal body or base A. This body has formed therein ports or channels A' 40 and A². Leading respectively into these parts are tubular channels B and B'. The channel B is provided with a coupling b, which connects to a tube b'. This tube leads directly from the main air-reservoir of any suitable 45 air-brake system, which reservoir is adapted to supply compressed air for the operation of the brakes, which air is passed through and controlled by my improved device. Connected to the tubular channel B' is a coupling 50 b², which connects to the tube b³, which leads

to and connects with any suitable train-line of air-brakes.

Tapped into the port or chamber A' is a tube C, which may be connected to any suitable air-gage adapted to register the condition of the air in the main reservoir, and tapped into the channel A² is a similar tube C', adapted to connect with the gage for indicating the train-line pressure.

Leading outwardly and upwardly from the channel A' is a port 1, which is adapted to communicate with a port 2 of a circular plate D, which is securely attached to the body A and is ground thereon, whereby an air-tight joint is maintained between the two said parts, 60 which are practically integral with each other.

The channel A² has two branches leading from its point of outlet, one of which leads into a port 3 of the plate D and the other into port 4 of the said plate. The two ports 2 and 65 3 of this plate D are adapted to engage with 70 a port 5 of a revoluble valve E, which said valve is smoothly ground to the upper surface of the plate D, whereby said plate acts as a seat for the valve and an air-tight joint 75 between valve and seat is maintained. The said valve is adapted to revolve around a spindle F, which is securely attached to the body A. Said valve is further provided through its periphery with a segmental port 80 6, adapted for engagement with the port 4 of the plate D for exhausting the air from the train-line.

Secured to the top surface of the valve E is a handle or lever E', which has a depending spring-tongue e attached thereto. This tongue is adapted to engage with radial projections or stops d', d², and d³ of the stationary plate D.

To maintain the valve E in secure vertical 90 engagement with its seat D, I provide a coil-spring G, which bears at its upper portion upon the lower face of a collar g, which is secured around the upper portion f of the spindle F.

Adjacent to the collar g is a similar collar g', and between these two collars are ball-bearings g² for reducing friction in operating the valve. The said parts are all held to the spindle F by means of a nut F', which is se- 95 100

cured to the outer end of the portion *f* of the spindle *F*.

Leading through the body *A* from the channel *A'* is a channel *7*, which communicates 5 with a port *8*. Said port leads into an annular chamber *9*, which forms part of the feed-valve *H*. The casing of said valve is tightly joined to the body *A* through the medium of bolts *a*.

10 Leading from the chamber *9* is a chamber *10*, which chamber is of a diameter considerably larger than the chamber *9*, and mounted upon an annular shoulder *11* of the chamber *10* is a metallic diaphragm *12*, which said diaphragm is held in place by means of a metallic ring *13* and a threaded plug *14*. This said plug is extended into a depending tubular projection *15*.

15 Formed within the channel which joins the chambers *9* and *10* together is a valve-seat *i*, which is adapted for engagement with the valve *I*, which valve is adapted to be closed by a spring *i'*.

20 Leading from the chamber *10* is a channel *16*, which communicates with a channel *17*, which said channel *17* communicates with a port *18* of the plate *D*.

25 Secured to the diaphragm *12* by means of a nut *j* is a stop *J*, which stop is adapted to engage with a seat *j'* of the plug *14*. The said stop is normally maintained in its unseated or open position by means of a coil-spring *K*, which is mounted upon a screw-plug *K'*, which is threaded within the lower 30 end of the tube *15*. By raising or lowering this plug the tension of the spring *K* can be gauged. Engaging with the outer edge of the plug *K'* is a screw-cap *k*, which acts as a jam-nut for maintaining the plug *K'* in position.

35 40 In the operation of the device, the valve *E* being set as indicated in Fig. 1 of the drawings, the air from the main reservoir will pass through the channel *A'*, thence up through the port *5* of the said valve and down into the channel *A²*, and thence through the tube *B'* to the train-line. When the handle is in running position, as indicated in Fig. 6, the main supply-port *1*, which leads from the channel *A'*, is closed. Air is then supplied from the main channel *A'* to the channel *7*, thence to the channel *8* into the chamber *9* of the feed-valve casing, thence to the chamber *10* and through the channels *16* and *17* to the port *18*, from said port to the port 45 50 55 of the valve, and thence down through the channel *A²* to the outlet *B'*, which leads to the train-line.

60 In order to exhaust the air from the train-line and work the brakes gently and slowly, the handle will be moved in the direction of the arrow *m* in Fig. 2 of the drawings until the port *6* of the valve *E* communicates with the extensions *s* and *s'* of the port *4*, whereby air will be exhausted from the train-line when making a slow and ordinary stop, but when

it is desired to make an emergency stop and exhaust air rapidly the handle *E'* of the valve *E* will be swung around to the stop *d*, whereby the port *6* of the valve *E* will register with the port *4* of the plate *D* and instantly exhaust the air from the train-line, whereby a full application of brakes will occur. 70

The feed-valve *H* is adapted to maintain a full supply of air in the train-line under a uniform pressure, and the cavities *9* and *10* will be maintained in relative positions by changing the tension of the spring *K*. For instance, there is one hundred pounds pressure in chamber *9* and seventy pounds in chamber *10*, the same pressure (seventy 75 pounds) being maintained in the train-line. Now any excess of pressure will force the stop *J* down upon its seat and close the valve *I*. The coil-spring *K* being set at seventy pounds pressure, if a leak should occur in the 80 train-line the pressure in cavity *9* is reduced, causing the spring to move the valve *12* upwardly, thus allowing air to pass into the port *16* and thence to the train-line, as before described. When seventy pounds is again 85 reached, the diaphragm is forced down and the valve *I* is again seated.

Having thus described my invention, what I claim as new, and desire to secure by Letters Patent, is—

95

1. In a brake-valve, a casing comprising a solid valve-body having two ports, a removable valve-seat provided with three ports ground to the said valve-body, a removable valve mounted on a spindle secured in the 100 solid valve-body, a handle for operating the valve, spring-actuated means for securing the valve in engagement with its seat, ball-bearings for reducing friction in operating the valve, and a feed-valve mechanism, substantially as shown and described.

2. An improved brake-valve, comprising a solid base or body having two ports therein and a removable valve-seat having three ports therein ground thereto, channels leading 110 therethrough respectively from a source of air-supply and to a train-line of brakes, said channels communicating with a revoluble valve having a port therein for connecting the two said channels together, and a further 115 port for exhausting air from the channel communicating with the train-pipe, the said body having further channels formed therein which communicate respectively with the said supply-channel and with the said revoluble valve; 120 and a feed-valve which engages with the two last-named channels and comprises a hollow body having a diaphragm, a spring-pressed valve and a stop therein for regulating the pressure in the train-line, substantially as 125 shown and described.

3. The combination of the metallic body having an inlet connected to an air-supply, an outlet-channel leading to a train-line, the revoluble valve for connecting the said chan- 130

nels, and the plate or seat for said valve ground thereon, the spring-pressed means, said means consisting of the collars with interposed roller-bearings and springs for maintaining it in engagement with its seat, and the operating-lever which is connected to the said valve; with the feed-valve comprising the compartmental casing having a valve, a regulating-diaphragm therein and the springs for operating the said parts, and channels for connecting the feed-valve chambers with

the inlet and outlet channels of the said body, substantially as shown and described.

In testimony that I claim the foregoing as my invention I have signed my name, in presence of two witnesses, this 27th day of May, 1896.

WILLIAM JAMES BRADLEY.
